UNITED STATES PATENT OFFICE.

EMORY GLENN SIMPSON, OF DETROIT, MICHIGAN, ASSIGNEE TO FISHER BODY CORPORATION, OF DETROIT, MICHIGAN, A CORPORATION OF NEW YORK.

WINDOW-LIFTER.

1,276,277.

Specification of Letters Patent. Patented Aug. 20, 1918.

Application filed August 18, 1917. Serial No. 186,834.

To all whom it may concern:

Be it known that I, EMORY GLENN SIMPSON, a citizen of the United States, residing at Detroit, county of Wayne, State of Michigan, have invented a certain new and useful Improvement in Window-Lifters, and declare the following to be a full, clear, and exact description of the same, such as will enable others skilled in the art to which it pertains to make and use the same, reference being had to the accompanying drawings, which form a part of this specification.

This invention relates to window lifters. It has for its object a window lifter that is positive in its action of raising the window and forcing it over the fence and raising the window off from the fence and dropping it over the window well.

In the drawings:

20 Fig. 1 is an inside elevation of an automobile door frame, the trimming being removed.

Fig. 2 is a vertical section on the line B—B of Fig. 1.

25 Fig. 3 is an enlarged detail of the lifting pin and the thrust and pulling cam.

Fig. 4 is an enlarged detail showing the position of the parts when the window is nearing the top of its travel, when the window has reached the upper extreme of its travel, and when the window has been dropped over the fence.

30 Fig. 5 is an enlarged detail partly in section, and taken from the opposite side of the view shown in Fig. 3, indicating how the window is thrust over the fence.

Fig. 6 is a perspective of the thrust and pulling cam.

Fig. 7 is a detail of the plate which carries the window.

40 *a* designates the door frame, the trimming of which has been removed. This door frame with the trimming in place forms a window-well *b* into which the window drops when lowered. Two sprocket wheels *c* and *d* form carriers for an endless chain *e* which carries a lifting pin *f* that engages in a horizontal slot *g* of the plate *i* which is secured to the lower sash rail *j*. The latter is provided with a turned-over flange or hook *k* which is adapted to hook over the fence *l*. This much of the construction is old.

45 The lifting pin does not bear directly against the plate *i* but a slidible collar *m* is interposed between the lifting pin and the

edges of the slot. This avoids objectionable friction between the edges of the slot and the lifting pin when the window moves axially of the pin when being pushed over the fence or drawn back from the fence. The 60 plate *i* is provided with an opening (Fig. 7) for leading to the horizontal slot *g*. This allows the window and sash to be lifted out of the window-well and disengaged from the lifting apparatus when the window has 65 reached its highest position. This makes a very easy way of disassembling the window from the rest of the apparatus when it is desired to repair it or inspect it.

Suitable locking devices to lock the window 70 in any position of raising or lowering and which are automatically disengaged when the handle is turned can be located in the casing *o*, but inasmuch as these are old in the art, they are not shown nor described. 75 Also a counter-balancing spring may be located in the larger portion of the housing *p* but inasmuch as these are old, they are not shown nor described.

80 The thrust and pull cam is a separate member from the lifting pin and is attached to a succeeding link of the chain. It comprises such a member as shown in Fig. 6 being a stamping with the web *r* secured to the chain, flange *s* and a tilted wiper *t*. The 85 plate *i* has a depending portion upon the left side, see Fig. 4, and a lower portion of this is bent to form an incline *u* (Fig. 5). Secured to the lower portion of the plate by riveting is a smaller plate *v* (Fig. 4). This 90 has a tail portion twisted out of the plane of plate *v* to form an incline *w* that parallels the incline *u*. These two, therefore, form an incline groove whose inclination is substantially that of the wiper *t* of the cam. 95

100 In lifting the window from the fence, the operation is as follows: The sprocket wheel (Fig. 4) is rotated counter-clockwise. This causes the lifting pin to raise the sash and the hook *k* off from the fence to the position shown in Fig. 5. In a further turning movement, the lifting pin having reached its maximum height causes the wiper *t* of the cam to enter the top of the incline cam-way (Fig. 5). Now very obviously this incline 105 wiper is going to bear upon the incline *w* and pull the window to the left, as shown in the dotted lines of Fig. 5. After the cam has passed through the cam-way the window continues in a descending movement. In 110

lifting the window the operation is simply reversed, the cam enters the cam-way at the bottom and being guided therein by the turned-over nose of the incline *w*.

5 It is evident from the above description that a simple efficient lifting and lateral movement mechanism is afforded which is positive in action, requiring no springs to assist in the movement.

10 What I claim is:

1. In a window lifter, the combination of a wheel, a linear member running thereover, a plate having a contact-portion, a lifting device engaged between the linear member 15 and the plate, and a cam upon a succeeding portion of the linear member which engaging with the said contact-portion pushes the window laterally over the fence and pulls it laterally from over the fence at the required time.

2. In a window lifter, the combination of a wheel, a linear member running thereover,

a plate for carrying the window, lifting connections between the plate and the linear member, the said plate being provided with 25 an inclined way, and a cam having a wiper adapted to engage in said inclined way to force the window over the fence and pull it away from the fence at the required time.

3. In a window lifter, the combination of 30 a wheel, a linear member running thereover, a plate for carrying the window provided with a portion bent into an incline, a second incline secured to the plate substantially paralleling the first incline to form an incline way and a cam secured to a portion of the chain and provided with a wiper adapted to travel in the cam-way between the two inclines to push the window over the fence and pull it away from the fence at the ap- 35 40 pointed time.

In testimony whereof, I sign this specification.

EMORY GLENN SIMPSON.
